VOTING MACHINE

Alvin N. Gustavson, Bemus Point, N. Y., assignor
to Automatic Voting Machine Corporation,
Jamestown, N. Y., a corporation of Delaware

Application July 31, 1945, Serial No. 608,037

3 Claims. (Cl. 235—54)

1

This invention relates to an improvement in voting machines and more particularly to a structure by which to control certain kinds of voting such, for example, as cumulative voting for general assembly, and is a continuation in part of my application, Serial No. 472,344, filed January 14, 1943, now forfeited.

In the disclosed form the invention comprises a mechanism that is adapted to be mounted in a voting machine, being located in close proximity to the main grouping channel of the machine. It may be removed and reinstalled in other machines or left as a permanent installation in the first machine in which it is installed. The type of voting machine to which the invention is particularly adaptable includes a multiplicity of indicator operable interlocking straps. Any desired groups of these straps may be connected with and controlled by the mechanism to both enable and require a voter to ballot in accordance with given election laws.

In certain areas provision is made for cumulative voting such as for voting for representatives in general assembly. Even in these areas local election requirements vary and in a particular example, a voter by law is given three votes with respect to the candidates for representative to general assembly and may distribute these three votes among the candidates of his own party or among the candidates of his own and other parties. A voter may cast all three votes for a single candidate, one vote for each of three candidates, or split his vote and cast one and one-half votes for each of two selected candidates.

The present invention is particularly directed to the provision of a voting machine mechanism that enables and controls cumulative voting and this, therefore, constitutes one of the objects thereof.

Another object of the invention lies in the provision of a cumulative mechanism that is readily installable and includes relatively few easily operable parts.

Other objects and advantages will be more fully understood from a consideration of the following specification taken in conjunction with the accompanying drawings; and in which

Fig. 1 is a front elevational view of a portion of the keyboard of a voting machine that has been arranged for voting on candidates for representatives in general assembly;

Fig. 2 is a fragmentary rear elevational view of that portion of the main grouping channel together with interlocking straps with which the

2

cumulative mechanism is intended to be associated;

Fig. 3 is a rear elevational view of the cumulative mechanism attached to the main grouping channel;

Fig. 4 is a perspective view of the cumulative mechanism being shown from the side that is applied to the main grouping channel;

Fig. 5 is an end and partial sectional view of the mechanism and main grouping channel, being taken substantially as indicated at 5—5 of Fig. 3;

Fig. 6 is an enlarged fragmentary view of the main grouping channel, parts being broken away to show the strap, roller and compensator relationship;

Fig. 7 is an elevational view of the cumulative mechanism with the parts in the position concerned with casting one and one-half votes for each of two candidates;

Fig. 8 is a view similar to Fig. 7, showing the position of the mechanism parts when a voter casts one vote for each of three candidates; and

Fig. 9 is a still further view of the mechanism with the parts in a position permitting the voter to cast three votes for a single candidate.

Reference is more particularly had to the drawing wherein the numeral 10 is employed to generally designate a portion of a voting machine keyboard. This keyboard is standard with voting machines to which the invention is applicable and includes a multiplicity of horizontal rows of indicators 11. Each indicator, through a well known mechanism is capable of registering a vote

35 on a suitable counter subsequent to being moved to a downwardly directed position with the pointed end of the indicator overlying the name of a candidate on the ballot label 12. In Fig. 1 of the drawing the voting machine is shown set up for

40 cumulative voting with six candidates, this illustration being for the sole purpose of disclosing the applicability of the invention to multiple cumulative voting. It will be noted that each candidate A, B, C, D, E, F, appears three times

45 on the ballot labels 12 and are arranged in three groups X, Y, Z. For clarity the left hand group of candidates includes a numeral one which signifies that a voter may cast only one vote for from one to three candidates in group X. In group Y there appears the numeral one and one-half under each of the candidates names which signifies that a voter can cast one and one-half votes for each of two candidates. In group Z, the numeral 3 is shown to designate that a voter

50 55 may cast three votes for one of the candidates.

Thus it is possible for a voter to cast one, one and one-half or three votes for any one candidate, or, if casting a single vote for one candidate, may cast a single vote for one or two other candidates, but he is not permitted to cast two votes for a single candidate.

Each of the indicators of a voting machine of the type disclosed, is connected with and serves to actuate an interlocking strap designated by the numeral 13. Each strap includes a ledge or shoulder 14, the lower end of the strap being formed with a neck 16 and an enlarged end 17. The neck and end 16 and 17 project into a main grouping channel 18, which forms a conventional part of the voting machine and includes a pair of spaced apart plates 19 having inwardly opening channels 21 that receive the enlarged ends of rollers 22. For convenience, the space between each pair of rollers accommodates the neck and end 16 and 17 of two straps, the enlarged ends being in opposed relation. When one of the indicators 11 on the face of the machine is manipulated the corresponding strap 13 is raised, causing the end 17 thereof to move upwardly between and laterally spread apart the rollers with which it is associated. To control the number of straps that may be raised in this manner, suitable grouping pins 23 and compensators 24 are provided. The grouping pins serve to generally limit movement of the rollers, whereas the compensators provide additional limitation to movement of the rollers and thus control the number of enlarged ends 17 of the straps that may be brought into position with the rollers within a group of any given size.

In the present illustration of the invention, that portion of the main grouping channel 18 under consideration is arranged with four grouping pins 23 that serve to provide three distinct groups corresponding to the groups X, Y, and Z already noted in connection with the candidate arrangement on the face of the machine. In group X, although six candidates are listed, only three may be voted for, and three compensators 24 are therefore positioned in this group. In group Y there are six candidates, only two of which may be voted for on the basis of one and one-half votes each and four compensators are provided. Similarly, in group Z, where only one of the six candidates may be voted for, five compensators are provided.

The mechanism by which a voter may selectively cast three ballots, in accordance with election requirements heretofore mentioned, is generally indicated by the reference numeral 26. This mechanism includes an upright portion 27, the lower edge of which is formed with a base or mounting flange 28 that terminates short of the ends of the portion 27. At the ends are horizontal flanges 29 which terminate in laterally spaced upstanding lugs 31 and 32. The lugs serve not only to engage the under edge of one of the grouping channel plates 19 but also to properly space the mechanism with respect to the channel. Suitable spacing studs 33, on the portion 27, abut a channel plate 19 and also serve as a means of positioning the mechanism. The struckout flanges 34 provide pivotal support for hooks 36 which, in the present showing, project through openings 37 formed by the flanges 34. One end of each hook is pivotally joined to a clamping screw 38 which projects through a support 39 carried by the portion 27. The upper end of the screw is threaded to receive a nut 41 and, when the mechanism is mounted as shown

in the drawing, the nuts 41 are rotated and the hooks 36 tilted downwardly, causing them to engage the lower edges of opening 42 formed in the outermost plate 19 of the grouping channel.

5 Pairs of flanges 43 on the portion 27 serve as a support for three aligned shafts 44, 45 and 46. Although these shafts are illustrated as of the same length they are only so made because of the convenience of use in connection with the 10 particular voting set-up. Mounted adjacent the ends of each of the shafts are arms 47, the free ends of which are connected by rods 48, 49 and 50. Each rod has several reduced diameter areas 51, the purpose of which will hereinafter be set out. Mounted on shafts 44 and 46 are additional arms 52 and 53 respectively. The corresponding 15 ends of each of these arms engage rods 48 and 50 and are formed with apertures 54.

Pivottally mounted on one face of the portion 20 27 is a pair of cam plates 55 and 56. Plate 55 includes an arm 57, the end of which projects through opening 54 of arm 52 carried by shaft 44. This plate also includes a cam arm 58. Plate 56 is identical with plate 55, being reversely 25 disposed and includes an arm 59, the end of which projects through opening 54 in arm 53, carried by shaft 46. Plate 56 includes a cam arm 60. One end of a plate 61 is joined to rod 49. The other end of this plate is fitted with a pin 30 62 that projects through an opening 63 in the portion 27 and, on the opposite side, is positioned by guide and securing means in the form of a washer 64 and pin 65.

Operative connection between cam plate 55 35 and plate 61 is provided through an arm 66 pivottally supported at one end on the portion 27 and at the other end formed with a pin 67 that projects through a slot 68 in the portion 27. This pin assumes either of two positions with 40 respect to the arm 58, namely, on the inclined surface or on the upper edge thereof (compare Figs. 7 and 9). A bar 69 is mounted for slidable movement on the portion 27 through the use of pin and slot structures 71 and 72. One end of 45 this bar is formed with an inclined edge 73 that is adapted to contact pin 67. The other end of the bar is formed with an inclined edge 74 engageable by a pin 76. This pin projects through a slot 71 in the portion 27, being carried by the 50 free end of an arm 78, that is pivottally mounted on the portion 27. One edge of the arm 78 includes an incline 79 located adjacent a notched out portion 80.

Operative connection between the cam plate 56 55 and the plate 61 is provided through the use of parts quite similar to those utilized to connect plates 55 and 61. That is, a pivot arm 81 is provided with a pin 82 projecting through a slot 83 in the portion 27, this pin being engageable with 60 the inclined edge 84 of a slideable bar 86. The other end of the bar 86 is straight edged as distinguished from the corresponding bar 69 and contacts a pin 87 projecting through slot 77 that is carried by the free end of an arm 88. One edge 65 of this arm includes an inclined surface 89 located adjacent a notched out portion 90.

As clearly shown in the Gustavson Patent No. 2,303,396, the mechanism 26 is connected with the interlocking straps 13 through the use of grouping straps 91, which at one end have spaced parts connected by lugs 92. The parts continue parallel for a short distance and then bend inwardly toward each other to form a connecting link 93, the lower end of which terminates in a hook 94. These straps are of a size to enclose a vertical

group of interlocking straps, this group being of a size corresponding to the number of horizontal rows of indicators on the voting machine. The hook 94 of each such group of straps is engaged with one of the areas 51 of the rods 48, 49 and 50, and the lug 92 thereof rests upon the conventional ledges or shoulders 14 of the straps 13.

The structure of the cumulative mechanism and its association with a voting machine having been described, operation thereof is as follows: It is assumed that a voter has elected to cast his three votes in the manner prescribed in group X, that is, a single vote for one, two or three of the six candidates listed. The first indicator 11 that a voter moves into vote indicating position elevates the corresponding grouping strap 91 and raises shaft 50. Upward movement of this shaft causes cam plate 56 to swing upwardly from the position of Fig. 4 into the position shown in Fig. 8. Such movement of plate 56 has caused certain other parts of the mechanism to be moved. Arm 81 has been swung about its pivot, contacted edge 84 of plate 86, moving this plate in a direction to cause it to swing arm 88 into contact with arm 78. As arm 78 is thus moved, the pin 76 thereof contacts the inclined surface 74 of plate 69, moving said last mentioned plate to a position such that the pin 67 of pivot arm 66 overlies the arm 58 of cam plate 55. It may thus be observed that as long as cam plate 56 is elevated for voting in group X, the mechanism will not permit simultaneous voting in either groups Y or Z. However, should a voter desire to change his type of balloting from that of casting a single vote for one, two, or three candidates as prescribed in group X and, for example, cast a single ballot of three votes for one candidate as required in group Z, he may actuate the desired indicator 11 on the face of the machine and such movement of this indicator will raise bar 48 and cam plate 55. This movement of cam plate 55 causes the movable parts of the mechanism to change from the position of Fig. 8 to that of Fig. 9. In other words, pin 67 has now been forced, by action of arm 58, to travel in the opposite direction, moving bar 69 to cause reverse swinging movement of arms 78 and 88. Thus bar 86 is moved and the inclined surface thereof, by contact with pin 82, causes said pin to ride up the incline of, and overlie, arm 60. It is to be particularly noted that in voting, in either group X or Z, plate 61 does not function except to swing from one position to another, substantially as indicated in the drawing. By way of further example, should the voter again wish to change his mind and cast two single votes of one and one-half each after he has mistakenly indicated his group preference in group X or Z, he need merely actuate an indicator 11 in group Y and this will raise a strap 91 in this group, thus elevating rod 49. Upward movement of this rod raises plate 61 and the attached pin 62 acts to separate or spread apart arms 78 and 88. This spreading of these arms causes slide bars 69 and 86 to move in opposite directions, or in a direction such that pins 67 and 82 will be caused to overlie arms 58 and 60 of cam plates 55 and 56. The extent of upward movement of pin 62 is such as to bring it into contact with the inclined surfaces 79 and 89 of arms 78 and 88. It will be understood that the angularity of these surfaces, together with the extent of pivotal movement of arms 78 and 88 and the various inclined surfaces 73, 74 and 84, is such that either rod 48 or 50 may be raised and such movement will cause arms 78 and 88 to come together in a manner to force

pin 62 downwardly into the position shown in either Figure 8 or 9 from the position shown in Figure 7.

As has already been brought out, a voter is limited to the casting of three votes in group X through the provision of three compensators in a portion of the main grouping channel set aside for this group. Similarly, four compensators are provided in the main channel for group Y in order that only two indicators may be actuated and, of course, five compensators are provided in a further portion of the main channel set aside for group Z to allow, in the present illustration of the invention, only one indicator to be actuated.

From the foregoing it should be clearly evident that a voter not only has the option, in connection with cumulative balloting, of casting single votes for each of three candidates, one and one-half votes for each of two candidates, or three votes for one candidate, but may also change his mind at any time during the period in which he is merely indicating his vote by movement of one or more indicators on the face of the machine. Of course, the mechanism by which a voter's indicated preference is registered cannot be actuated to any extent and still permit the voter to change his group selection any more than he could make a change under these circumstances with any other type of voting. The mechanism by which all indicators are prevented manipulation from commencement of the registering operation is neither shown nor described since it is well known and has been in use many years on voting machines of the type to which this invention is applicable.

Although applicant has shown and described only one specific form of his invention, it will be understood that various modifications may be made and are contemplated insofar as such modifications are within the spirit and scope of the invention as defined in the annexed claims.

Having thus set forth my invention what I claim as new and for which I desire protection by Letters Patent is:

- 45 1. In a voting machine, a plurality of interlocking straps, three movable members, means segregating said straps into groups and providing connection of said groups with said members, swingable plates operatively associated with the end members, a pair of arms operatively associated with the intermediate member, a pair of slideable bars operatively connecting the plates of the end members with said arms, said plates, arms and bars having such cooperative movement, 50 when one end member is moved to an operative position, as to secure the remaining members and their connected groups in an inoperative position.
- 55 2. In a voting machine, a plurality of interlocking straps, three movable members, means 55 segregating said straps into groups and providing connection of said groups with said members, linkage operatively connected with one endmost member, other linkage operatively connected with the other endmost member, a plate joined 60 to the intermediate member, a pair of pivotal arms 65 cooperative to engage said plate in a manner to move said intermediate member into an inoperative position, and bars operatively connecting said arms with the linkage of said endmost members 70 whereby movement of either endmost member into an operative position causes said linkage and bars to actuate said arms to withdraw the intermediate member from an operative to an inoperative position.
- 75 3. In a voting machine, a plurality of inter-

locking straps, three movable members, means segregating said straps into groups and providing connection of said groups with said members, swingable plates operatively associated with the endmost members, a plate joined to the intermediate member, a pair of pivotal arms cooperatively movable in a manner to engage said plate and move the intermediate member into an inoperative position, bars operatively connecting said swingable plates with said arms, said plate, 10 by movement of the intermediate member into an operative position, moving said arms in a manner to actuate either of said bars and the

5 associated swingable plates to move an endmost member from an operative to an inoperative position.
